UNITED STATES PATENT OFFICE.

JOHN ANDREWS, OF MARLBOROUGH, MASSACHUSETTS, ASSIGNOR TO HIMSELF AND ASHLEY BRIGHAM, JR., OF SAME PLACE.

IMPROVEMENT IN FASTENERS FOR THE MEETING-RAILS OF SASHES.

Specification forming part of Letters Patent No. 122,348, dated January 2, 1872.

To all persons to whom these presents may come:

Be it known that I, JOHN ANDREWS, of Marlborough, of the county of Middlesex and State of Massachusetts, have invented a new and useful Improvement in Window-Sash Fasteners; and do hereby declare the same to be described, as follows, and represented in the accompanying drawing, of which—

Figure 1 denotes a top view, Fig. 2 front elevation, and Fig. 3 an end view of my new sash-fastener as applied to the next adjacent horizontal bars of the upper and lower sashes of a window. It is designed to be used upon windows whose sashes have a middle vertical bar to the upper or each of them.

With window-sashes so made it has been customary heretofore either to use with the two sashes two fastenings arranged on opposite sides of the middle upright bar of the upper sash; or, in the place of two fasteners so disposed, a single fastener placed aside of the said bar, such bar being an obstruction or impediment to the arranging of the fastener at the middle of the contiguous horizontal sash-bars—that is, the bottom bar of the upper sash and the top bar of the lower sash.

Owing to the construction of my improved fastener it can be applied to the middle of the said contiguous bars, as it will straddle the middle vertical bar of the upper sash.

In the drawing, A denotes the pivotal frame or carrier of the locking lever-catch B. The

said catch, instead of having its point *a* at the middle of the carrier A, as usual, has it disposed on one side of and at a distance from such middle, as shown, the carrier being provided or constructed with a notch or opening, *b*, to receive the middle upright bar *c* of the upper sash. The said notched carrier straddles the bar *c*, and rests on and is fastened by screws *d d* to the lower horizontal bar *e* of the upper sash. The locking-lever or arm-catch B is formed with a bend or elbow, as shown at *f*, and the catch-plate C is constructed with half (*g*) of its latching-flange concentric with the pivot of the catch-arm B, the remainder or other half *h* of the flange being correspondingly shaped, the same being so that the part *h* may not only serve as a finish to the catch-plate, but as a stop to arrest the catch-lever when at the middle of the catch-plate. The elbow of the catch-lever is to cause the straight part *i* of such lever to stand square or at right angles with the sashes when they are fastened.

I claim—

The combination of the carrier-plate A notched or recessed at *b*, the bent arm or lever B pivoted at *a*, and the double-curve flanged catch-plate C, all substantially as described and shown, and for the purpose set forth.

JOHN ANDREWS.
